United States Patent Office.

ANDREW GILBERT, OF BOSTON, MASSACHUSETTS.

Design No. 4,563, dated January 10, 1871.

DESIGN FOR TYPE.

The Schedule referred to in these Letters Patent and making part of the same.

I, ANDREW GILBERT, of Boston, in the county of Suffolk and State of Massachusetts, have invented and produced a new and original Design for the Faces of Types, representing the letters of the English alphabet, of which the following is a specification.

In the drawings are seen the letters of two alphabets, both of the same design, one representing the capitals and the other the small, or, technically, the lower-case letters.

The capital letters, as seen in the drawing, have their upright, technically, the broad lines, composed of three lines or marks, the center one thick and the two outer ones light or shade lines. They also have a projection from each side of the upright lines, at the middle of the same, in the shape of three loops, side by side, which are produced by the outer or shade lines being curved in that shape.

The lower-case letters are made with the upright or broad lines composed of one thick line, and to the right of the same one light or shade line, and, technically, the weight of the letter or its deepest shading and most prominently distinguishable feature is formed by angular-shaped figures, whose sides are concavely curved, one at top and one at bottom of the broad line; and

What I claim herein as of my own invention, and desire to secure by Letters Patent, is—

The design of the said type, as described and shown.

ANDREW GILBERT.
